JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS

FURNACE-CHARGING MECHANISM

Application filed February 7, 1929. Serial No. 338,195.

The present invention relates in general to furnace-charging mechanism. In particular, the invention is concerned with the charging to and handling within a furnace, of successively delivered flat billets or slabs, which, on account of their width, cannot be handled in the same manner as narrower stock. When narrow stock is charged, a short-stroke broadside pusher can be used within the furnace, and each subsequently delivered bar or billet can be guided on one side by the wall of the furnace and on the other side by the billet which has been moved out of charging position by said short-stroke pusher. 10 When wide stock is being charged, each piece must be pushed, broadside, well down the inclined supporting hearth or floor, and hence it can afford no guidance for the next piece charged onto the horizontal receiving portion 15 of said hearth. According to the invention, the required guidance is supplied, by the cooperative action of a fixed interior surface, such as the furnace wall, and an outside guiding device effective against the other edge of 20 the slab or billet, whereby the latter is accurately positioned on the hearth in full-length edgewise contact with said wall, before the broadside movement is imparted. Furthermore, this guidance and control, as exercised 25 upon each piece entering the furnace, enables any already-charged piece to be pushed from behind by the piece immediately following to the far end of the hearth, if said furnace is wide enough to accommodate two or more 30 bars arranged end to end in alinement; in consequence of this, the action of the broadside pushers will cause the slabs or billets to travel sidewise through the furnace in a plurality of rows.

Other and further objects of the invention will be apparent from the following detailed description thereof, reference being had in this connection to the accompanying drawings, in which—

Fig. 1 is a top plan view, partly in section,

showing the furnace-charging mechanism of my invention.

Fig. 2 is a large scale sectional view of the charging end of the furnace, showing the operation of the broadside pusher devices. 50

Fig. 3 is a view similar to Fig. 1, illustrating the operation of the mechanism in forming two rows of bars for movement broadside through the furnace.

Figs. 4 and 5 are diagrammatic views in horizontal section, illustrating different stages in the operation of feeding a piece of stock into the furnace. 55

Fig. 6 is a plan view, showing, on a larger scale than Figs. 1 and 3, the exterior guiding means of the charging mechanism. 60

Like reference characters refer to like parts in the different figures.

Referring first to Fig. 1, the furnace A, which may be of conventional construction, provides in its side wall 1 the usual charging opening 2, through which each of the successively delivered billets or slabs is projected endwise. Within the furnace, each piece is received on a horizontal supporting portion 3 of the hearth, preparatory to the action thereon of broadside pushers 4, 4 that operate, as shown in Fig. 2 to push each piece broadside onto the inclined portion of the hearth or floor, the latter formed in part, as here shown by the inclined skids 5, 5; by this action a row of pieces is formed, which has a step-by-step broadside movement through the furnace. 75

As shown in Fig. 2, each pusher 4 has a link connection 29 to a common operating rock shaft 30, the latter being journaled in brackets 31, 31 on the outside of the rear wall 6 of the furnace. An arm 32 secured to said rock shaft 30, derives motion through a connecting rod 33 from a crank or eccentric 34. Each operation of the latter procures movement in unison of all the pushers 4, 4, from the full line retracted position of Fig. 2 to the broken line position of the same figure, 90

and then back again to retracted position. In handling relatively wide stock, as illustrated at *a* in Fig. 2, this broadside pusher movement by which the stock is shifted from the horizontal receiving portion 3 onto the inclined skids 5, 5, must be sufficient to allow the broadside-moving piece to tip over into a condition of flatwise support on the inclined skids before coming into edgewise contact 5 with the piece immediately ahead of it on said inclined hearth; in other words, unless the piece being transferred broadside to the inclined skids 5, 5 can have more than one-half of its width projected beyond the 10 section line 36 of skids 5 and hearth 3, without engaging the piece 35 preceding it on said skids, the moving piece would be subject to buckling, and might even tend to over-ride the previous piece 35. Hence, in handling 15 within a furnace such relatively wide pieces or slabs, the broadside pusher mechanism must be given a relatively long stroke,—the stroke being of such length that each piece is moved entirely off the horizontal receiving 20 portion 3, and cannot therefore provide any guidance for the movement onto such receiving portion of the next-arriving piece.

To provide such guidance, and to secure the correct positioning of each piece within the 30 furnace before commencement of its broadsiding movements, as well as the straightening, as far as possible, of pieces that arrive in a warped or curved condition, my invention contemplates the provision of means, exterior 35 of the furnace for cooperation with the end wall 6 thereof, to square up each piece edge-wise with the inner surface of said wall,—thus eliminating the necessity for using devices, located inside the furnace, for this purpose. Such interior devices, as exemplified 40 by the skewed rollers of Edwards and Carroll Patent No. 701,023, dated May 27, 1902, being subject at all times to the intense heat of the furnace interior, can have only a relatively 45 short life. My invention obtains the same results as such interior devices, without exposing any operating parts to the high temperature of the furnace chamber.

To this end, as shown in Fig. 1, the successive pieces to be charged are caused to approach the opening 2 in such a manner as to be impinged upon and pressed against the wall 6; this can be accomplished, for example, by delivering the stock on a series of conveyor rollers 7, 7, which may be driven by suitable gearing from a common operating shaft 8, and which preferably have their axes skewed in such manner as to produce, concurrently with the endwise movement of the 55 conveyed piece toward the opening 2, a side-wise or edgewise movement toward a longitudinal guide 9. In other words, this approach of the conveyed piece toward the opening 2, is preferably such as to carry the 60 advancing end of said piece out of line with

said opening, and on the opposite side of said opening from the end wall 6 of the furnace. To guide the piece toward said opening 2, from its above described out-of-line position, and more particularly to press it continually toward the wall 6, there is interposed between said series of skewed rollers 7, 7 and said opening 2 a guiding device, which includes a roller 10 for edgewise contact with the piece, immediately adjacent the 70 opening 2 on the outside of the furnace. 75

Said roller 10, as shown in Fig. 1, is carried by one arm of a bell crank lever 11, the latter being pivoted at 12 and having its other arm subject to the expansive force of a spring 13, whereby the roller 10 is yieldingly held in any given position as determined by the adjustment of the guide bracket 14, by which said roller 10 is carried. As shown in Fig. 1, said guide bracket 14, which carries the pivoted bell crank mounting 11 of roller 10, is itself pivotally mounted, as shown at 15, so that the position of said roller can be adjusted with reference to a fixed guide section 16, that keeps the front end of each piece 20 in position to enter the opening 2; any desired form of guide may be used for this purpose. A transverse slot 17 in the bottom of the fixed guide is provided for the passage of a bolt 18 that also passes through a slot 19 of guide bracket 14. By means of a nut 20 on bolt 18, the guide bracket 14 may be set and held in any position of angular adjustment within the limits afforded by said slots, thereby to dispose the roller 10 in the desired 25 relation to the opening 2, as determined by the width of the stock that is being fed to the furnace through said opening. 30

As shown in Fig. 4, and as above described, the arrangement of mechanism is such that each piece of stock, in its movement toward the opening 2, approaches and enters said opening from the side which is opposite to the guiding end wall 6, with the result that the front end of each piece has one corner 21 35 directed against said wall 6. Inasmuch as this oblique direction of movement through the opening 2 is maintained for nearly the entire length of the piece, and due to the fact that the spring 13, under compression because of the crowding action of the piece on roller 10, is constantly exerting its force to push the piece toward the wall 6, the engagement of corner 21 with said wall 6, as the 40 piece is moved farther and farther into the furnace, is maintained, as shown in Fig. 1, and finally, as shown in Fig. 5, the expansive force of spring 13 acts on the rear end of the piece to produce full-length edgewise contact of said piece with said wall. By this 45 time, of course, the piece is free of the skewed rollers 7, 7, but its complete movement into the furnace, in the absence of sufficient momentum imparted by said rollers 7, 7, is assured by pinch rollers 22, located in or near 50

the opening 2 and driven in any suitable manner, as through gearing 23 from a motor 24.

The piece thus charged into the furnace and resting on the horizontal hearth portion 3 in full-length edgewise contact with the end wall 6, can now be acted upon by the broadside pusher devices, as hereinafter described in detail, with definite assurance that such action will inaugurate the orderly step-by-step broadside travel of the piece down the inclined furnace floor 5, 5; such action is assured, in the absence of buckling, because of the control and guidance exercised upon the piece during the charging operation to establish its full-length edgewise contact with the end wall 6. If the furnace be wide enough, as shown in Fig. 3, to accommodate two or more rows of bars, charged endwise thereto, the first bar, as indicated at 25, with its edge in contact with the end wall 6, is followed immediately by a second bar 26, whose feed into the furnace is effected in precisely the same manner as above described, and whose front end, pushing against the rear end of bar 25, secures the movement of the latter to the far side of the furnace, without disturbing the ultimate squared-up relation of either bar to the guiding end wall 6. The broadside pushing action, whether the bars be charged singly, for the formation of one row, or in tandem, for the formation of two or more rows, is the same, and is accomplished by pushers 4, 4 that, in the usual manner, occupy a retracted position, in apertures 27, 27 of end wall 6, while each single bar, or each set of bars in tandem, is being fed through the opening 2.

I claim:

1. In mechanism of the class described, the combination with a furnace having a charging opening, adjacent its rear wall, of means for procuring the approach of each bar towards said opening from the side of said opening which is remote from said wall, thereby to project a front corner of said bar against said wall, and means for maintaining said corner in contact with said wall as the bar continues to advance into the furnace, said last-named means operating to thrust the rear end of the bar toward said wall, thereby to establish full-length edgewise contact of said bar with said wall.

2. In mechanism of the class described, the combination with a furnace having a charging opening adjacent one wall thereof, of means comprising skewed rollers, exterior of the furnace, to advance each bar toward the furnace in out-of-line relation to said charging opening, and means interposed between said rollers and said furnace for directing the advancing end of said bar obliquely through said opening, thereby to procure contact of one front corner of said bar with said furnace wall.

3. In mechanism of the class described, the

combination with a furnace having a charging opening adjacent one wall thereof, of means comprising skewed rollers, exterior of the furnace, to advance each bar toward the furnace in out-of-line relation to said charging opening, and means interposed between said rollers and said furnace for directing the advancing end of said bar obliquely through said opening, thereby to procure contact of one front corner of said bar with said furnace wall, said last-named means adapted to exert a yielding pressure on said bar to maintain said contact and to finally procure the full-length edgewise contact of said bar with said furnace wall.

4. In mechanism of the class described, the combination with a furnace having a charging opening, adjacent one wall thereof, of means exterior of the furnace for procuring, by yielding pressure against one edge of each bar charged, the full-length contact of the opposite edge of said bar with said furnace wall.

5. In mechanism of the class described, the combination with a furnace having a charging opening, adjacent one wall thereof, of means exterior of the furnace for procuring, by yielding pressure against one edge of each bar charged, the full-length contact of the opposite edge of said bar with said furnace wall, said last-named means being adjustable to bars of different widths without effect on the pressure exerted thereby.

6. The combination with a furnace having a charging opening adjacent its rear wall, of a pair of pinch rollers adjacent said opening to procure the longitudinal movement of the stock into the furnace, and means in advance of said pinch rollers for guiding the stock between the same, and for maintaining the longitudinal axis of said stock, during its movement by said rollers at an acute angle to said rear wall of the furnace.

7. Furnace charging mechanism of the class described, comprising a series of skewed rollers for the combined forward and sidewise movement of the stock, in its passage toward the charging opening of the furnace, and guiding means interposed between said skewed rollers and said charging opening for imparting to said stock a sidewise deflection in opposition to the sidewise movement imparted by said skewed rollers, thereby to maintain the stock in its passage through said opening at an acute angle to the axis of said opening.

8. In mechanism of the class described, the combination with a furnace having a charging opening adjacent one wall thereof, of means exterior of the furnace for establishing substantially full-length contact of each bar charged through said opening with said furnace wall, said means comprising a fixed guide, substantially parallel with said wall, at one side of said opening, and an adjustable

device, pressing yieldingly against each bar at the other side of said opening.

9. In mechanism of the class described, the combination with a furnace having a charging opening adjacent one wall thereof, of means exterior of the furnace for establishing substantially full-length contact of each bar charged through said opening with said furnace wall, said means comprising a spring-pressed guide member adjacent that side of said opening which is farthest from said wall, and means for causing each bar to fulcrum on said guide member, in its passage through said opening.
